UNITED STATES PATENT OFFICE.

HENRY T. DAGGETT, OF SOUTH BRAINTREE, MASSACHUSETTS.

IMPROVEMENT IN SIDING BOOTS AND SHOES.

Specification forming part of Letters Patent No. 79,733, dated July 7, 1868.

To all whom it may concern:

Be it known that I, HENRY T. DAGGETT, of South Braintree, in the county of Norfolk, and State of Massachusetts, have invented an Improvement in "Siding Up" Boot-Legs; and I do hereby declare that the following, taken in connection with the drawing which accompanies and forms part of this specification, is a description of my invention sufficient to enable those skilled in the art to practice it.

In siding up boot-legs the pieces of leather, cut to proper form, are laid one upon the other with the outer surfaces together, (the narrow welt being between the edges to be stitched together,) and it is always desirable to bring the row of stitches as near as possible to the edge consistently with security against breaking through of the stitches when the leg is turned, such close proximity of the stitches being desirable in order to prevent too great protrusion of the stitched edge within the boot-leg when the boot is finished or worn; but as the heel-counter is made of stout thick stock, and as it is therefore necessary to carry the stitches farther from the edge upon the counter to prevent them from breaking out (in turning) by the greater strain upon them caused by the thickness and rigidity of the counter-leather, the stitches are run equally far from the edge along the whole length of the leg, it being impractical to stop the stitch-forming mechanism when the counter is reached in order to change the distance of the stitch-forming line from the edge, and equally impractical under the present method of siding up to change the edge-gage (which regulates the distance of the edge from the path of the needle) during the sewing process.

The object of my invention is to so arrange a sliding gage that it may be readily slid back by the operator without stopping the machine, the edge-gage being clamped by the position of the actuating mechanism without the use of any specific clamping device, so that while sewing very near the edge all along the boot-leg down to the counter the gage may be instantly slipped back when the counter is reached; and my invention consists in combining a sliding gage with a mechanism for throwing it back (while the sewing is progressing) to a determined distance, corresponding to the difference between the distance at which the stitches on the counter should be run and

that at which it is desirable to place the stitches between the top of the boot-leg and the counter.

The drawing represents the edges of a boot-leg thus sided up and a gage with mechanism for throwing it back.

A shows an edge view of the boot-leg; B, a plan of the edge; C, a plan of the gage mechanism; D, a vertical section thereof. *a* denotes the back leather, and *b* the front leather, of the boot-leg; *c*, the lining cemented to the inner portion thereof; *d*, the welt inserted between the adjacent surfaces of *a* and *b*, the edges of the two pieces to be stitched together being cut to match, and the surfaces which are to be outward in the finished boot being placed together to be stitched. *e* denotes the heel counter or stiffener, formed of hard thick stock to give proper rigidity to the boot-leg at the heel. *f* denotes the gage, against which the edge of the combined pieces are held for the action of the stitch-forming mechanism. This gage is mounted and slides in guides *h*, and on a horizontal plate, *i*, and at its rear end it is jointed to an arm, *k*, which is connected by a link, *l*, with a lever, *m*, said lever being fulcrumed at *n* to an upright, *o*, against the inner face of which the end of the arm *k* is drawn by a spring, *p*. The inner end of the gage-slide *f* has a slot, *g*, through which extends a spindle or pin, *r*, projecting up from the plate *i* and through a slot, *s*, in the lever *m*, this spindle having at its upper end a screw-thread, upon which works a nut, *t*, the position of the nut determining the extent of upward movement of the lever. When in normal position the arm *k* is in horizontal line with the gage-slide *f*, and the front or guiding face of the gage is projected out, so as to be in position for guiding the edge of the boot-leg above the heel-counter, it being held in such position by the position of the arm *k*, as denoted by the red lines at D.

Now, when the leg is fed along and the stitching reaches the counter (where such stitching should extend farther in from the edge, as before described) the operator lifts the lever *m*, thereby causing the link *l* to lift the arm *k* into inclined position, the gage *f* being thereby left free to be drawn back by the spring *p*, so that, the stock being still held up to the gage, the stitching will be effected at the required distance from the edge of the counter, the nut

t stopping the lever, and thereby the gage, as will be readily understood. Thus the space between the seam and the edge is left desirably narrow where the stock is thin and soft, and is made as wide as may be necessary across the counter. The gage-plate *i* is made with adjusting-slots *u*, to regulate by means of screws the distance of the main line of stitching from the edge of the stock, and by means of the screw-nut *t* the change of width at the counter may be made greater or smaller, in accordance with the thickness of the counter. By these means it will be readily seen that the siding up of boot-legs may be much more

satisfactorily effected than with a stationary gage.

The specific mechanism may be varied, though I consider the arrangement shown to be substantially the best one.

I claim—

For use in siding up boots and shoes, the combination of the gage *f* with the mechanism for changing its position, substantially as and for the purpose set forth.

HENRY T. DAGGETT.
